UNITED STATES PATENT OFFICE.

EBERHARD GRASSHOFF, OF BOCHUM, GERMANY, ASSIGNOR TO C. OTTO UND COMP. GESELLSCHAFT MIT BESCHRAENKTER HAFTUNG, OF BOCHUM, GERMANY.

COKE-PUSHING MACHINE.

Application filed March 30, 1927, Serial No. 179,695, and in Germany May 3, 1926.

It is well-known to fit the pusher head of coke pushing machines with glide rollers or glide shoes, as with modern coke ovens having chambers of a length of 12 m and 5 more, the pusher bar for the machine bends through to such an extent, that the pusher head comes aground on the chamber floor on the rear portion of the chamber, toward the coke side of the oven. Neither these 10 glide rollers, however, nor the shoes usually mounted on the pusher bar directly behind the head have been able to diminish the wear of the chamber floor. With said shoes which drag over a great portion of the 15 floor, this fact is to be understood without any explanation, as the friction existing between the iron shoes and the floor of the chamber, which consists of refractory bricks, is considerable, in particular as the pressure 20 exerted on the surface of the shoe likewise assumes high values due to the heavy load by the pusher head and bar. The use of glide rollers was likewise unable to substantially remedy said drawback of the chamber 25 floor being worn out. For, already after a very short time the rollers seize in their bearings, as this is unavoidable due to the high temperature prevailing in the chamber and to the unavoidable penetration of coke dust 30 in the bearings of said rollers. The rollers then act in a very noxious manner as grinding disks and mill grooves in the floor of the chamber. To obviate these drawbacks, it has already been proposed to employ so-called freely supported pusher bars, that 35 means bars which bend through, even with greatest lengths of the chambers, only to such an extent that the pusher head does not touch the floor. Pusher bars of this type, however, must be of a very strong construction 40 in comparison with the usual bars, this causing a considerable increase of the costs of the entire pushing machine.

Now my invention has for its object to 45 utilise the advantages of both said types of pusher bars without presenting their drawbacks, that is to maintain the lighter structure of the pusher bars hitherto used and therewith to considerably lower the first 50 costs of the machine, and on the other hand, to prevent with certainty any running aground of the pusher head.

In order to allow my invention to be more 55 easily understood, two embodiments of same are illustrated in the drawing which accom-

panies and forms part of this specification. On this drawing:

Fig. 1 shows the parts of a coke pushing machine and of an oven chamber in a lateral view, partly in section, 60

Fig. 2 is a similiar view of the second embodiment of the coke pushing machine.

The embodiment shown in Fig. 1 will be described first.

A coke pushing machine *a* is adapted to travel on the machine side along the coke oven battery, the machine being fitted in the usual way with a pusher bar *b* carrying a pusher head *c*. A supporting shoe *d* is arranged below the pusher bar *b* and may 65 run, for instance by means of anti-friction rollers *e*, above track *f* fixed on the bar *b*. Further antifriction rollers *g* are mounted below said track on the supporting shoe *d*, the distance of which from the rollers *e* 70 preferably is so chosen, that the rollers *g* are out of contact with the bar *b* as long as the upper rollers *e* rest on the track *f*. The pusher bar *b*, pusher head *c*, and shoe *d* are arranged so as to reciprocate within the 75 oven chamber.

The described machine operates as follows:

When the pusher bar *b* is being retired to such an extent, that the pusher head *c* is outside the oven chamber, the supporting shoe *d* rests on the track *f* directly behind the head *c*. Now the pusher bar *b* is forwarded. Its bending resistance is so determined, that the pusher head *c* is firstly held in freely supported condition. When the bar *b* is further forwarded, the bending moment acting upon the bar *b* increases, so that the bar successively bends more and more. By suitable selection of the conditions it may be obtained, that the supporting shoe *d* touches the floor about in the middle 90 of the chamber. The great friction on the floor causes the supporting shoe to stop at this point, as shown in Fig. 1. When this 95 stoppage takes place, the bar *b* thence glides along the rollers *e* until it comes to rest upon the lower rollers *g* with increasing bending. In the further pushing motion the rollers *g* 100 form a support for the bar *b*, so that the freely supported portion thereof which carries the head *c*, is considerably shortened. It is obtained in this manner, that the pusher head *c* is held freely supported even in the 105 portion of the chamber located towards the 110

coke side. The supporting shoe *d* is of a construction permitting it to come aground on the floor without the pusher head *c* coming aground, with a corresponding bending of the bar. As the supporting shoe drags on the floor only a little or does not drag at all, a saving of the floor is obtained by the described arrangement which has not been reached hitherto. In returning the pusher bar *b* the inverse stage takes place, as evident.

The embodiment shown in Fig. 2 substantially differs from that described in so far as the shifting motion of the supporting shoe *d* is limited by an automatically released locking gear. To this end a bell-crank lever *h* is mounted for rocking motion about pivot *k* on the shoe *d*, one arm *h*¹ of which lever is adapted to loosely engage a keeper, such as eye *c*¹ fixed on the pusher head *c*, whilst its other arm *h*² is attached to a pull rod *i*. This rod extends up to the cabin *a* of the machine, where it is suitably guided, and carries a lug *i*¹ adapted to stop the bar *i* in its extreme position, shown in Fig. 2. When the pusher bar *b* is forwarded, the supporting shoe *d* is firstly connected to the head *c* by the arm *h*¹, an eye *c*¹. When the supporting shoe *d* reaches the middle of the chamber, the lug *i*¹ of the pull rod *i* strikes on a stop arranged in the cabin of the machine. This causes the bell-crank lever *h* to execute a rocking motion about its pivot due to the further forward motion of the pusher bar *b*, whereby the arm *h*¹ of the bell-crank lever *h* is lifted out of the eye *c*¹, the lock existing between the supporting shoe and the pusher head *c* thus being released. The supporting shoe is maintained in this position and comes to rest on the floor due to the pusher bar *b* bending down. The stage taking place with further forwarding of the pusher bar *b* is the same as described with reference to the first embodiment. When the pusher bar *b* is moved in, shoe *d* and pull rod *i* are returned so that the lever arm *h*¹ is automatically rocked about pivot *k* and engages again the eye *c*¹. The supporting shoe *d* thus being locked again with the pusher head *c* is returned together with it. This automatic engagement is brought about, in the form of the invention illustrated, by the rod *i*, which, because of its friction in its supporting bearing in the house *a*, rocks the bell-crank *h* as the shoe *d* is returned, when the shoe is struck by the pusher head *c*. This embodiment offers the further advantage that the supporting shoe is unable at all to drag on the floor of the chamber and comes aground always at a predetermined place due to the releasing of the shoe *d* from pusher head *c*.

What I claim as my invention and desire to secure by Letters-Patent, is:—

66. 1. In a coke pushing machine for coke ovens a pusher bar adapted to reciprocate,

a pusher head mounted thereon and a member, separate from said pusher head, slidably connected with said bar and arranged below said bar, said pusher head and member reciprocating within the oven chamber, said member coming aground on the floor of the oven, independently of said pusher head, as the pusher bar bends down in the pushing operation. 75

2. In a coke pushing machine for coke ovens a pusher bar adapted to reciprocate, a pusher head mounted thereon, a track arranged on said bar, a member running on said track and arranged below said bar, said member coming aground on the floor of the oven chamber as the pusher bar bends down in the pushing operation, and antifriction means carried by said member above and below said track. 83

3. In a coke pushing machine for coke ovens a pusher bar adapted to reciprocate, a pusher head mounted thereon, a member slidably connected with said bar and arranged below said bar, said member coming aground on the floor of the oven chamber as the pusher bar bends down in the pushing operation, and antifriction means arranged below said bar between said bar and said member contacting with said bar 90 after said member has come aground. 95

4. In a coke pushing machine for coke ovens a pusher bar adapted to reciprocate, a pusher head mounted thereon, a member slidably connected with said bar below the bar, said member coming aground on the floor of the oven chamber as the pusher bar bends down in the pushing operation, means for locking said member in a position near said pusher head, and means for releasing 105 said locking means.

5. In a coke pushing machine for coke ovens a pusher bar adapted to reciprocate, a pusher head mounted thereon, a member slidably connected with said bar below the bar, said member coming aground on the floor of the oven chamber as the pusher bar bends down in the pushing operation, means for locking said member in a position near 110 said pushing head, and means for automatically releasing said locking means after a predetermined forward motion of said pusher bar. 115

6. In a coke pushing machine for coke ovens a pusher bar adapted to reciprocate, a pusher head mounted thereon, a member slidably connected with said bar below the bar, said member coming aground on the floor of the oven chamber as the pusher bar bends down in the pushing operation, a locking means movably mounted on said member, a keeper provided on said pusher head and engaged by said locking means, a pull rod connected to said locking means to actuate it, a lug arranged on a stationary part of 120 125 130

the machine, and a stop face on said pull rod cooperating with said lug to stop said pull rod after a predetermined forward motion of said pusher bar, so as to release the locking means.

7. In a coke pushing machine for coke ovens a pusher bar adapted to reciprocate, a pusher head mounted thereon, a member slidably connected with said bar below the 10 bar, said member coming aground on the floor of the oven chamber as the pusher bar bends down in the pushing operation, a bell

crank lever pivotally mounted on said member for rocking motion one arm of said bell crank lever releasably engaging said pusher head, a pull rod connected to the other arm of said bell crank lever, a lug arranged on a stationary part of the machine, and a stop face on said pull rod cooperating with said lug to stop said pull rod after a predetermined forward motion of said pusher bar.

In testimony whereof, I have signed my name to this specification.

E. GRASSHOFF.
